DESIGN FOR A COMBINED TIE CLIP AND PENCIL

Richard B. Maxwell, Brooklyn, N. Y.

Application September 9, 1946, Serial No. 133,200

Term of patent 7 years

(Cl. D74—24)

To all whom it may concern:

Be it known that I, Richard B. Maxwell, a citizen of the United States and residing at Brooklyn, in the county of Kings and State of New York, have invented a new, original, and ornamental Design for a Combined Tie Clip and Pencil, of which the following is a specification, reference being had to the accompanying drawing, forming part thereof and in which

Fig. 1 is a front elevational view of a design of a combined tie clip and pencil in accordance with the present invention, showing a pencil attachment therefor.

Fig. 2 is a side elevational view.

Fig. 3 is a back elevational view,

Fig. 4 is a top view; and

Fig. 5 is a bottom view.

I claim:

The ornamental design for a combined tie clip and pencil, substantially as shown.

RICHARD B. MAXWELL.
